DESIGN FOR A SPECTACLE FRAME

Altina Barrett and Eric Barrett,
Beverly Hills, Calif.

Application October 25, 1944, Serial No. 115,974

Term of patent 14 years

(Cl. D57—1)

To all whom it may concern:

Be it known that we, Altina Barrett and Eric Barrett, citizens of the United States, residing at Beverly Hills, in the county of Los Angeles and State of California, have invented a new and original Design for a Spectacle Frame, of which the following is a specification, reference being had to the accompanying drawing, forming part thereof.

In the drawing,

Fig. 1 is a top view of a spectacle frame showing our new design;

Fig. 2 is a side view from the left of the spectacle frame shown in Fig. 1; and

Fig. 3 is a view of the right side thereof.

The essential features of our design for a spectacle frame reside in the portions shown in full lines in Figs. 1 to 3, inclusive, and the same are characterized by a plurality of curved dividing lines at the forward end of the temple piece.

We claim:

The ornamental design for a spectacle frame, substantially as shown and described.

ALTINA BARRETT.
ERIC BARRETT.
